(57) **CLAIM**

The ornamental design for a kiosk panel as shown and described.

DESCRIPTION

FIG. 1 is a front right perspective view of a first embodiment of a kiosk panel showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom view thereof;

FIG. 8 is a front right perspective view of a second embodiment of a kiosk panel showing my new design;

FIG. 9 is a front elevation view of the second embodiment;

FIG. 10 is a rear elevation view of the second embodiment;

FIG. 11 is a right side elevation view of the second embodiment;

FIG. 12 is a left side elevation view of the second embodiment;

FIG. 13 is a top plan view of the second embodiment; and, FIG. 14 is a bottom view of the second embodiment.

The broken lines shown in FIGS. 1-14 illustrate portions of the kiosk panel that form no part of the claimed design. The portions having the plus-sign stippling indicate portions of a first color or a first material, while portions having the dotted stippling indicate portions of a second color or a second material, the second color or second material being different than the first color or first material.
